(57) **CLAIM**

The ornamental design for a vehicle parking-assist curb, as shown and described.

DESCRIPTION

FIG. 1 is a perspective view of the vehicle parking-assist curb;

FIG. 2 is a front view of the vehicle parking-assist curb;

FIG. 3 is a rear view of the vehicle parking-assist curb;

FIG. 4 is a left side view of the vehicle parking-assist curb (where the right side view is a mirror image of the left side view);

FIG. 5 is a top view of the vehicle parking-assist curb; and,

FIG. 6 is a bottom view of the vehicle parking-assist curb. The broken lines depict portions of the vehicle parking-assist curb that form no part of the claimed design.
